ELECTRIC HEATER FOR CIRCULATING FLUIDS

Application filed November 24, 1930, Serial No. 497,909, and in Germany November 29, 1929.

The present invention relates to an electric heater for heating circulating fluids of the kind in which a primary winding system is arranged round an iron jacket tube, and a 5 short-circuited tubular coil system as a secondary circuit is wound coaxially round the primary system; the heater serves for heating gases and liquids.

An electric heater according to the invention is illustrated in the accompanying drawings wherein

Fig. 1 is a sectional elevation of the device,
Fig. 2 is a sectional plan and

Fig. 3 is a sectional elevation of one phase 15 of a modification.

The electric heater according to the present invention consists of a primary winding system arranged round an iron jacket tube, and a short-circuited tubular coil system as a secondary circuit wound co-axially round the primary system. The internal cross section of the heat producing jacket tube carrying the coils is much greater, for instance, ten times, than that actually required for conducting 20 the fluid to be heated. By the sudden alteration of the cross section in passing from the conducting pipes to the greatly enlarged jacket tubes the fluid to be heated is given a whirling motion in the latter; the heat 25 change is thus promoted. By the insertion of a displacement block having a corresponding cross section into the part of the jacket tube forming the heat-producing surface, the space required for the fluid to flow through 30 the tube is narrowed in such a manner that the fluid to be heated passes through the space between the displacement block and the interior surface of the heated tube in a velocity which is the most favorable for the transmission 35 of heat. The length and position of the displacement block in the jacket tube is determined by the primary coil surrounding the jacket tube.

In some cases it may be possible that the 40 number of coil turns required for providing the desired heating surface is larger than that required for the production of the secondary active current. In this case the length of the primary coil is such that it covers only so 45 many secondary turns as are necessary for

the production of the required secondary active current. The remaining secondary turns act as a series resistance; heat is thus produced also in these turns. This form is of a particular advantage if for chemical 55 reasons iron cannot be used for the part of the apparatus through which the fluid flows, necessitating the use of aluminium, for instance; in this case the actual resistance of the secondary part is increased. In this instance cast-iron cylinders carrying the heat-resistant primary coils are fitted round the jacket tubes made of aluminium.

Experience has shown that it is unnecessary to close the magnetic circuit, because the 60 energy of the primary ampere turns is completely utilized by the massive iron inside the coils.

In the accompanying drawings Fig. 1 shows a sectional elevation of the electric 65 heater according to the invention. The fluid to be heated enters by the pipe H and is uniformly distributed into the three jacket tubes A by the star-shaped connecting pipe C₂; the three branches are united in the socket G attached to the distributing pipe E. From the latter spring the three tubular secondary coils D which are connected at their other ends with the discharge outlet F. The changes in the velocity of the current of fluid 70 have the special advantage of ensuring a thorough mixing of the fluid to be heated. In the jacket tubes A there are inserted displacement blocks J which cause the fluid to be heated to pass at the desired velocity along 75 the walls heated by the heat-resisting primary coils B. As the cross section of the jacket tube A is considerably greater than that of the connecting pipes C₁ and C₂—in the present case 12.5 times—it is possible to 80 provide a large heating surface at the primary part and to get on with a low number of turns of the primary coils B; thus a considerable quantity of copper is saved and the apparatus is simplified.

Fig. 2 is a sectional plan of the apparatus and particularly illustrates the arrangement of the jacket tubes and the tube coils.

Fig. 3 illustrates a form in which the jacket tube may be of aluminum. The jacket tube 100

is surrounded by a cast-iron cylinder K having a suitable thickness of wall. The cylinder carries the heat-resisting primary coil L, which is surrounded by the secondary tubular coil M. The length N of the primary coil is such that only so many turns of the tubular coils N are in the field as are required for the production of the secondary energy. The displacement block J extends in the axial direction of the jacket tube only so far as the cast-iron hollow cylinder is surrounded by the primary coil.

We claim:

1. Electric heater for circulating fluids 15 with a primary winding system fitted round an iron jacket tube and a short-circuited tubular coil system as a secondary circuit wound co-axially round the primary system,

in which heater the internal cross section of the heat-producing jacket tube carrying the coils is about 10 times larger than the internal cross section of the inlet pipe and in which a displacement block is arranged in the jacket tube in order to obtain the optimal velocity of the current of the fluid to be heated, the length and position of the displacement block being determined by the primary coil surrounding the jacket tube.

2. In the electric heater for circulating fluids referred to in claim 1 the modification which consists in the primary coil extending in the axial direction only over a part of the turns of the coil.

EMIL FENDT.
CARL SCHÖRG.
